UNITED STATES PATENT OFFICE.

MERRILL W. GALLAWAY, OF NEW YORK, N. Y.

SAFETY APPLIANCE FOR GAS-STOVES AND THE LIKE.

1,322,894.

Specification of Letters Patent.

Patented Nov. 25, 1919.

Application filed November 25, 1914. Serial No. 874,058.

To all whom it may concern:

Be it known that I, MERRILL W. GALLAWAY, a citizen of the United States, residing at New York city, New York, have invented 5 certain new and useful Improvements in Safety Appliances for Gas-Stoves and the like, of which the following is a clear, full, and exact description.

This invention relates to safety appliances for gas stoves and the like and has 10 for its object more particularly the provision of means for preventing the accidental opening of the gas cocks of such stoves. It is well known that children too young 15 to understand any better will often open the cocks of a gas stove in a mischievous way and consequently run the danger of asphyxiation if not discovered in time. To guard against such dangers as well as accidental opening of the gas cocks by older 20 people I have devised a simple safety appliance adapted to be attached to a gas stove, the preferred embodiment of which is shown in the accompanying drawings, in which—

25 Figure 1 is a plan view of the device; Fig. 2 is a front elevation of the same;

Fig. 3 is a modification of the same looking from the rear along $x-x$ of Fig. 1; and

30 Fig. 4 is a detail section along line $y-y$ looking in the direction of the arrows.

Referring more particularly to the drawings, 1 indicates the ordinary gas inlet pipe for a gas stove from which the branches 2 extend to the several burners of the stove. 35 In the present embodiment I have shown five of these, but it is of course obvious that the present invention is applicable to any number. Each of the inlet branches 2 is controlled by the usual gas cock 6 having 40 a handle 3 and a stop-pin 4, working in a slot 5 to limit the rotatable movement of the cock from its open to its shut position. All of this is common in gas stoves and will be readily understood.

45 Preferably my safety appliance is in a form to be detachably mounted upon the stove in the following manner: A bar 7 is mounted adjacent the manifold pipe 1 by means of brackets 9 and 10, said bar being 50 slidably supported on the brackets by means of screw studs 12, 13, of the bracket and slots 11, 14, of the bar as shown. Extending upwardly from the bar 7 are a plurality of projecting portions 8, each adapted to 55 stand in the way of a handle 3 of one of

the cocks 6 when the bar is in the position shown in Fig. 2. This is the locking position for the bar and it is obvious that when so located none of the handles 3 can be turned to open its respective gas cock, and thus the stove is guarded against the accidental opening of the cocks. In order to secure the bar in its locking position it is provided in the present embodiment with a pivoted catch 15 pivotally mounted by stud 65 20 in bearings of bar 7, and having a slotted engagement with a pin 19 of said bar 7 to prevent falling too far out of position. The forward end of said catch is beveled as at 17, and has a notch 17' for engagement with 70 a pin, such as 18, upon some stationary portion of the stove. It will be understood that when the bar 7 is moved to the left looking at Fig. 3, for instance, from its dotted line position to its full line position 75 as shown, that the catch 15 will ride by its beveled edge over pin 18 and automatically engage with the same so as to prevent the bar being moved back. The pivot 20 is fixed to the catch 15, and for convenience 80 of handling the pivot 20 of said catch 15 is provided at its outer end with a knurled knob 21 so that when said knob is turned the catch will be raised. Also by means of the knob 21 the bar 7 may be moved back 85 and forth to its locking or unlocking position. This in some cases is sufficient for operating the bar 7.

Fig. 3 shows a modification of the device in which means are provided to automatically move the bar 7 to its locking position when the gas cocks are closed. This consists more particularly in the present embodiment of a spring 22 connected to a stationary portion 21' of the frame and to one of 90 the projections 8 of the bar 7, said spring tending at all times to move the bar 7 toward the left looking at Fig. 3. It is understood that the gas cocks 6 are sufficiently tight in their bearings so that any 95 one of said cocks when opened with its handle 3 standing in the way of a projection 8 of said bar 7, will prevent the bar moving to its locking position under stress of spring 22, but as soon as all of said gas cocks are 100 closed the bar 7 will then move to its locking position under the stress of the spring 22. It is also obvious that other positive means may be provided between the cock 6 and 105 the bar 7 to prevent movement of the bar 110

to locking position when any one of the cocks are open. When the bar 7 is moved to locking position, the catch 15 will of course then automatically engage with pin 18 and the 5 gas cocks of the stove will be guarded against accidental opening. To open any one of the cocks the knob 21 is slightly turned first to release the catch and then moved toward the left, looking at Figs. 1 10 and 2, to carry the projections 8 of bar 7 away from behind the handles 3 of the cocks.

It is understood that the present disclosure is merely one of the preferred embodiments of my invention and that various 15 changes and variations may be made without departing from the spirit of the invention as claimed.

What I claim as new is:—

1. In a safety appliance for gas stoves 20 and the like, the combination with one or more cocks adapted to be opened and closed for controlling the admission of gas to said stove, of locking means tending at all times to move into locking position for preventing 25 the opening of said cocks when closed and constructed and arranged to be held in unlocking position by the opened cock, and a catch arranged to hold said locking means positively against movement out of its locking 30 position when so moved.

2. In a safety appliance for gas stoves or the like, the combination with a gas cock, 35 of locking means movable into and out of a position in which it locks said gas cock closed, means for positively preventing movement of said locking means out of locking position, and means acting automatically upon the closing of said gas cock to move said locking means into locking 40 position.

3. In a safety appliance for gas stoves or the like, the combination with a gas cock, 45 of locking means movable into and out of a position in which it locks said gas cock closed, means acting automatically upon the closing of said gas cock to move said locking means into locking position, and means automatically brought into operative position as said locking means is moved into locking position for positively preventing movement of said locking means out of locking 50 position.

4. In a safety appliance for gas stoves or the like, the combination with a gas cock, 55 of locking means movable into and out of a position in which it locks said gas cock closed, a latch for holding said locking means positively in locking position, and means acting automatically as said gas cock 60 is closed to move said locking means and said latch into their respective operative positions.

5. In a safety appliance for gas stoves or the like, the combination with a gas cock, 65 of locking means automatically movable

into a position in which it locks said gas cock closed and arranged to be held in unlocking position by the opened cock, a latch for holding said locking means positively in locking position constructed and arranged to be brought into holding position by the automatic movement of said locking means into locking position, and a handle arranged to be grasped to unlock said latch and to move said locking means out of locking 75 position.

6. In a safety appliance for gas stoves or the like, the combination with a gas cock, of locking means movable into and out of a position in which it locks said gas cock 80 closed and arranged to be held in unlocking position by the opened cock, means tending at all times to move said locking means into locking position, and a latch carried by said locking means and movable therewith, 85 when said cock is closed, into position to hold said locking means positively against movement out of locking position.

7. In a safety appliance for gas stoves or the like, the combination with a gas cock, 90 of locking means movable into and out of a position in which it locks the gas cock closed, means for automatically effecting the movement of said locking means into operative position, means automatically 95 brought into operative position by the movement of said locking means into locking position for positively preventing movement of said locking means out of locking position, and a handle for manipulating said preventing means and said locking means to bring them into respective inoperative positions, constructed and arranged to require two different movements to effect the manipulation of said two 100 means.

8. In a safety appliance for gas stoves and the like the combination with a plurality of cocks having operating handles so as to be opened and closed for controlling 110 the admission of gas to said stove, of locking means operable into locking position for preventing the opening of said cocks when closed and into unlocking position for releasing said cocks, comprising a bar provided with portions adapted to be shifted into the way of the handles of said cocks, and a spring tending at all times to move said bar into locking position, any one of said cocks when opened acting to prevent 115 the movement of said bar by said spring.

9. In a safety appliance for gas stoves or the like, the combination with a plurality of gas cocks, each having an operating handle arranged to swing from a closed position in which said handles are substantially in line into an open position transverse to said line, of locking means movable in a fixed path along said line and comprising a locking stop for each handle movable 125 130

from unlocking into locking position in the direction along said line of the closing movement of the handles, means, comprising a member carried by said locking means 5 and automatically brought into retaining position as said locking means is moved into locking position, for positively retaining said locking means against movement out of locking position, and a handle for 10 moving said locking means between its two positions, connected to said retaining means

and movable in one direction to release said retaining means and in another direction to effect the movement of said locking means.

15

Signed at New York city, N. Y., this 23rd day of November, 1914.
